Attorney

UNITED STATES PATENT OFFICE

MARY E. WOOD, OF KIRKSVILLE, MISSOURI

HAIR-WAVING IMPLEMENT

Application filed October 1, 1929. Serial No. 396,538.

This invention relates to implements of that type used for the purpose of imparting a permanent or a Marcel wave to the hair. Implement of this type that are now in use are objectionable for the reason that their cylindrical formation renders it impossible to form a permanent wave or a Marcel wave that will lie flat and hug the head, which is particularly desirable.

10 The present invention has for one of its objects to overcome the stated objection to implements of this character, and to obtain this end comprehends the provision of a hair waving implement which shall embody

15 a plate, knobs extending from one side of the plate and about which strands of the hair are to be bent backwardly and forwardly, and means for moving the knobs relatively to tighten or place the hair under tension.

20 The invention further comprehends the provision of a hair waving implement of the character stated which shall embody elements carried by the plate at opposite sides of the knobs so as to permit the hair to be placed 25 under the required tension as the result of the relative adjustment of the studs.

The invention still further comprehends the provision of a hair waving implement of the character stated which shall be adapted 30 to enable the waving operation to be completed in a comparatively short time, and which shall be capable of being manufactured and sold at a comparatively low cost.

The invention is hereinafter fully described and claimed and illustrated in the accompanying drawing, wherein:-

Figure 1 is a top plan view on an enlarged scale of the hair waving implement;

Figure 2 is a sectional view taken on the plane indicated by the line 2-2 of Figure 1;

Figure 3 is a sectional view taken on the plane indicated by the line 3-3 of Figure 1, and

Figure 4 is a detailed view illustrating the manner in which the adjustable knob is connected to the plate.

The hair waving implement comprises a metal plate 1 which is preferably flat and of elongated rectangular contour. The plate 20 is provided at its transverse center with a slot

2 which extends inwardly from one side edge and terminates short of the center thereof. A post 3 extends upwardly from one corner of the plate 1, and a post 4 extends longitudinally from that end edge of the plate 55 farthest from the post 3. The post 3 may be screw threadedly engaged with the plate 1 or secured thereto in any other suitable manner and it is provided at its upper end with an outwardly directed annular flange 3a. 60 The post 4 is arranged at the longitudinal center of the plate 1, is secured thereto by rivets 5, and is provided at its outer end with outwardly directed shoulders 4a.

Knobs 6 and 7 are secured by screws 7a to 65 the plate 1. The knobs 6 and 7 are arranged at one side of the longitudinal center of the plate 1 and at opposite sides of the transverse center of the plate. The knobs 6 and 7 are provided with convex outer surfaces 8 70 and concave inner surfaces 9, and are provided with lower flanges 10 and upper flanges 11. The flanges 10 of each of the knobs 6 and 7 extend from end to end of the post and lie in full abutting contact with the plate 1. The flanges 11 are shorter than the flanges 10 and are located centrally of the outer sides of the knobs 6 and 7. The upper surfaces of the flanges 10 incline downwardly and outwardly and the lower surfaces of the flanges 11 incline upwardly and outwardly.

A knob 12 is mounted upon the plate 1 opposite the knobs 6 and 7 and for adjustment toward and away from said knobs. The adjustable knob 12 is similar to the fixed knobs 6 and 7, and the convex outer side thereof is designated 8a, the concave inner side 9a, the lower flanges 10a and the upper flange 11a. The knob 12 is provided with a lug 13 which extends downwardly therefrom and through the slot 2 of the plate 1. The lug 13 is provided in its sides with grooves 14 which receive the side walls of the slots 2 to connect the knob 12 to the plate for sliding movement transversely thereof and to hold it against upward displacement from the plate. The lug 13 is provided at its lower end with a screw threaded opening 15 for the reception of an adjusting screw 16, which is located below the plate 1 and at the transverse center 95 160

thereof. The screw 16 is rotatably connected to the plate 1 by a bearing 17 which holds it against endwise movement. The screw 16 is provided at its outer end with an operating head 18.

In practice, the movable knob 12 is adjusted into its innermost position, this position being determined by the inner end wall of the slot 2. Strands of the hair are then 10 bent backwardly and forwardly around the knobs 6, 7 and 12 and in contact with the outer or convex surfaces of the knobs. The strands are then tied to the posts 3 and 4 by cord or the like. The knob 12 is then 15 moved away from the knobs 6 and 7 through the medium of the screw 16 to place the strands of hair under the required tension. Due to the flat formation of the plate 1 and to the longitudinal strain placed upon the bends 20 or curls of the hair strands, the desired wave will be formed and such wave will lie flat and hug the head. The instrument may be readily removed from the hair by adjusting the knob 12 in the direction of the knobs 6 25 and 7, and untying the strands from the posts 3 and 4. The flanges of the knobs 6, 7 and 12 prevent the strands of hair from becoming accidentally displaced from the knobs and the inwardly converging opposite surfaces of 30 the flanges tend to force the strands of hair in the direction of each other. The heads of the posts 3 and 4 prevent the cords used to tie the strands of hair from becoming accidentally displaced from the posts.

35 While I have described the principle of the invention, together with the device which I now consider the preferred embodiment thereof, it is to be understood that the device shown is merely illustrative and that such 40 changes may be made, when desired, as fall within the scope of the invention as claimed.

I claim:—

1. A hair waving implement comprising a plate, a post extending upwardly from the 45 plate, a post extending longitudinally from the plate, knobs fixed to the plate, a knob connected to the plate for adjustment away from said first knobs to place the strands under tension, and means for adjusting said 50 last knob.

2. A hair waving implement comprising an elongated rectangular plate, a post extending longitudinally from one end edge of the plate, a post extending upwardly 55 from the plate adjacent the opposite end edge thereof, knobs fixed to the plate, a knob mounted on the plate for adjustment away from said fixed knobs to place the strands under tension, and means for adjusting said 60 last knob.

3. A hair waving implement comprising an elongated rectangular plate, knobs extending upwardly from the plate and arranged in side by side relation at one side 65 of the longitudinal center of the plate, the

plate being provided at the other side of its longitudinal center and centrally between its end edges with a transverse slot, a knob extending upwardly from the plate and having a lug passing through said slot, an adjusting screw rotatably mounted on the bottom of the plate and engaged with the lug, a post extending longitudinally from one end edge of the plate, and a post extending upwardly from the plate near the other end edge 75 thereof.

4. A hair waving implement comprising a plate, knobs extending upwardly from the plate and arranged in parallel relation, the knobs being provided with convex outer surfaces and concave inner surfaces, a knob extending upwardly from the plate opposite the inner surfaces of said first knobs and extending across the adjacent ends of said first knobs, means for securing said last knob to the plate for adjustment toward and away from the inner surfaces of said first knobs, and means for adjusting said last knob.

5. A hair waving implement comprising a series of knobs arranged to provide a tortuous passage in which strands of the hair are to be arranged, means mounting the knobs to permit one to be adjusted away from the others to place the strands under tension, and means for adjusting the movable knob.

6. A hair waving implement comprising a series of knobs arranged to provide a tortuous passage in which strands of the hair are to be arranged, means mounting the knobs to permit one to be adjusted toward and away from the others, and means for adjusting the movable knob, the knobs being each provided with convex outer surfaces and upper and lower flanges having inwardly converging opposing faces.

7. A hair waving implement comprising a fixed knob and a movable knob about which strands of the hair are to be bent, and means for adjusting the movable knob away from the fixed knob to place the strands under tension.

8. A hair waving implement comprising a fixed knob and a movable knob about which the strands of the hair are to be bent, elements to which the strands are to be tied and having a fixed position with respect to the fixed knob, and means for adjusting the movable knob away from the fixed knob to place the strands under tension.

In testimony whereof I hereunto affix my signature.

MARY E. WOOD.
